DESIGN FOR A COMBINATION WINDING AND DRYING RACK

Mitchel Morgan, Brooklyn, N. Y.

Application September 14, 1938, Serial No. 79,897

Term of patent 3½ years

To all whom it may concern:

Be it known that I, Mitchel Morgan, a citizen of the United States, residing at Brooklyn, in the county of Kings and State of New York, have invented a new, original, and ornamental Design for a Combination Winding and Drying Rack, of which the following is a specification, reference being made to the accompanying drawing, forming part thereof.

Figure 1 is a perspective view of a combination

winding and drying rack showing my new design.

Figure 2 is a top plan view; and

Figure 3 is a side elevational view with the clamp and a portion of the clamp standard omitted for convenience of illustration.

I claim:

The ornamental design for a combination winding and drying rack, as shown and described.

MITCHEL MORGAN.
